CLAIM

The ornamental design for an combined electronic siren and handheld microphone, as shown and described.

DESCRIPTION

FIG. 1 is a front perspective view of our combined electronic siren and handle microphone showing a typical embodiment of our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear end elevational view thereof; and,

FIG. 7 is a front end elevational view thereof.
